INVALID'S BED

Marvel D. Beem and Allan J. Taylor, Los Angeles, Calif.; said Taylor assignor to said Beem, and said Beem assignor of one-half to The Beem Foundation, Los Angeles, Calif., a charitable trust of California

Application October 15, 1945, Serial No. 622,386

5 Claims. (Cl. 5—69)

1

This invention relates to an invalid's bed of the type used in hospitals, and is directed particularly to a mattress supporting mechanism of the type embodying hinged sections provided with lift mechanism for raising the sections to a reclining seat position.

A bed of this type ordinarily embodies a back rest, a leg rest and a thigh section hinged between the back and leg rest, with the hinge between the back rest and thigh section being attached to the fixed frame of the bed and the (knee) hinge between the thigh section and leg rest being free to move upwardly. In all such beds, the thigh section has a fixed length which is adapted to the person of average build. Abnormally short or abnormally tall persons, however, find that the thigh section is either too long or too short for maximum comfort. With this problem in mind, the invention has as its general object to provide a bed of the hinged section type in which the thigh section is adjustable for length.

Another object of the invention is to provide an adjustable thigh section bed in which the adjustment of the length of the thigh section does not materially increase or decrease the overall length of the mattress supporting frame.

A further object is to provide an adjustable thigh section bed in which adjustment of the thigh section may be accomplished with maximum simplicity and ease.

In general, the invention contemplates a bed in which there is a double hinge between the thigh section and the leg rest, with means for rigidifying either of the two hinges in order that only one of them may be operative. More specifically, the invention contemplates an arrangement wherein there is a short section interposed between the thigh section and the leg rest, hinged to each of these members, and adapted to assume a position in alignment with either of them.

A further object is to provide a relatively simple latch mechanism for rigidifying one of these hinges, with the other hinge being adapted to become automatically rigidified when the first mentioned hinge is freed from hinging action.

Another object is to provide a bed embodying a mattress supporting frame having improved means for supporting a mattress between pairs of adjacent sections and for causing the mattress to assume a properly curved position when the bed sections are elevated.

Other objects of the invention will become apparent from a perusal of the following specifica-

2

tion when taken in connection with the appended drawings, in which:

Fig. 1 is a side elevation of a bed embodying our invention;

Fig. 2 is a longitudinal sectional view through the seat portion of the bed, illustrating one of the double hinges in operative condition;

Fig. 3 is a similar sectional view illustrating the other of the double hinges in operative condition;

Fig. 4 is a detailed transverse sectional view taken on the line 4—4 of Fig. 1;

Fig. 5 is a detailed sectional view taken on the line 5—5 of Fig. 1;

Fig. 6 is a detailed sectional view taken on the line 6—6 of Fig. 1;

Fig. 7 is a longitudinal sectional view through a double hinge embodying a modified form of the invention; and

Fig. 8 is a transverse sectional view of the hinge shown in Fig. 7.

As an example of one form in which the invention may be embodied, we have shown in the drawings an invalid's bed comprising a supporting cabinet 10 having a head member 11 and a foot member 12 projecting upwardly therefrom, having utility drawers 13 and hinged panels 14 and 15, and having a panel 16 carrying a lavatory which may be as shown in the application Serial No. 591,099 of Marvel D. Beem, for Invalid's bed.

Referring to Figs. 2—5 inclusive, the bed is provided with longitudinally extending frame members 17 on which is supported a sub frame 18 having longitudinally extending side rails 19. The mattress supporting frame comprises a plurality of sections each having a bottom portion 20, on which the mattress 48 rests, and upwardly projecting side flanges 21, between the sides of which the mattress is positioned. The side flanges 21 are in the form of downwardly opening channels, in which the frame rails 19 are received.

The mattress supporting frame sections include the head rest section A, the intermediate thigh section B, and the foot rest section C. The foot rest section C is connected to the thigh section B by an intermediate section D and a pair of hinges 22 and 23. The intermediate section D comprises a pair of inverted channels 24 each connected to a flange 21 of the thigh section B by a hinge 22 and to the leg section C by a hinge 23. The legs of the channels 24 are trapezoidal in outline. A transverse rod 25, on which is hinged a pair of flaps 26 and 27, has its ends mounted in the channels 24. The edges of the flaps 26, 27 opposite the edges that are hinged

to the rod 25, overlap and rest upon the upper surfaces of the bottom members 20 of the frame sections B and C respectively, and slide upon these surfaces.

The back rest A is adapted to be elevated by suitable lift mechanism which is not shown but is similar to the lift mechanism for the thigh section B, which lift mechanism includes a pair of arms 28 hinged at 29 to the stationary frame 17 and having, at their ends opposite the hinge 29, rollers 30 which engage the under surface of the bottom member 20 of the thigh section B. The arms 28 normally lie substantially below the plane of the sub frame 19. They are pivoted at 31 to push rods 32 through which elevating movement is transmitted.

The thigh section B, as it is elevated, carries with it the leg rest C. The weight of the leg rest C, imposed upon the hinges 23, tends to rotate the intermediate section D downwardly around the axis of the hinges 22. Such downward movement of the section D may be prevented by a latch 33 which is pivoted at 34 to a side flange 21 of the thigh section B. The latch 33 is adapted to project into a slot 35 in the bottom member 20 to engage the edge of the flap 26. With the flap thus engaged, it is impossible for the intermediate section 24 to swing downwardly about the hinges 22. Instead, it is held in a position projecting in alignment with the side flanges 21 of the thigh section B as shown in Fig. 2.

The latch 33 may be provided with a lip 36 adapted to project over the upper surface of the flap 26 and prevent any possibility of the flap 26 slipping off the end of the latch 33 when compression is applied between the two members. The latch 33 is also provided with a lever 37 which extends upwardly and is provided with a handle 38 at its upper end. When the lever 37 is moved toward the head rest A, the latch 33 will be lifted above the flap 26, permitting the latter to slide beneath the latch and thereby allowing the intermediate section D to tilt downwardly about the hinge 22 to a position of alignment with foot rest section C as shown in Fig. 3. In this position, a pair of lugs 39 and 40 on the ends of the side plates of the channel 24, and the flanges 21 of the leg rest C will engage to provide a stop action which prevents the hinge 23 breaking downwardly and thus supports the foot rest C in alignment with the connecting section D as shown in Fig. 3.

It may now be noted that when the parts are in the position shown in Fig. 2, the flap 26 will cover a gap existing between the end of the bottom wall 20 of the thigh section B and the hinge 25, while in the position of the parts shown in Fig. 3, the flap 27 will cover a gap existing between the hinge 25 and the end of the bottom wall 20 of the leg rest C. In addition to its primary function of covering the gap, the flap 26 also serves as part of the means for latching the connecting section D in alignment with the thigh section B.

Lugs 41 and 42 on the channel 24 and flanges 21 of the thigh section B are adapted to engage when the thigh section B and intermediate section D are in alignment, to prevent the hinge 22 breaking downwardly. (See Fig. 6.) The lugs 39 and 40 are similar to the lugs 41 and 42.

The thigh section B and back rest A are hinged to each other and to the side rails 19 of the sub frame 18 by means of hinges 43. The ends of the flanges 21 and bottom walls 20 of the section A and B adjacent to hinge 43 are cut away as at 44 to leave a gap between such ends at all times.

This gap is of sufficient width so that there is no danger of any member that could be damaged, being caught therein. The gap is covered by a flexible sheet metal leaf 45 the edges of which are hinged to the back rest A and thigh section B at 46 and 47 respectively.

When the back rest A and thigh section B are in their lowered positions, the leaf 45 will be stretched in a flat plane as indicated in dotted lines. When the back rest A and thigh section B are in their positions of normal elevation shown in Fig. 2, the plate 45 will assume a broad curve coaxial with the axis of natural flexing of the mattress 48, which is of sponge rubber. The plate 45 is of spring material, and therefore will flex with a substantially uniform curvature.

In order to secure the proper amount of flexure of the plate 45 from a flat condition to a properly curved condition, the location of the axis of the hinge 43 (its spacing above the common plane of the bottom walls 20 when the latter are horizontal) is correlated to the spacing of the hinges 46 and 47 so that only a moderate amount of shortening of the distance between the hinges 46 and 47 will occur as the back rest and thigh section swing upwardly from their horizontal positions to their elevated positions. To this end, the axis of the hinge 43 is located intermediate the common plane of the hinges 46, 47 in their lowered positions and the common plane of the pivots 46, 47 in their elevated positions, and is somewhat closer to the former plane than to the latter. Also, there is a lost motion connection in the hinge 46 which permits the hinges 46 and 47 to spread as they move upwardly from the lower of the two aforesaid planes to a common plane for all three of the hinge axes 46, 47, 43. The lost motion connection may be effected by elongating one set of the hinge loops comprising the hinge 46 as indicated in Fig. 2.

In Figs. 7 and 8 we have shown an alternative hinge structure between frame members B', D' and C' which are composed of square, tubular structural members. The upper walls 49 of these tubular members are arranged to abut each other at their ends to prevent the hinges 22, 23 from breaking downwardly below their aligned positions, while the lower walls 50 are cut away at 51 to permit each hinge to break upwardly except when rigidified by a sleeve 52 which may be slid longitudinally over either of the hinges.

We claim as our invention:

1. In an invalid's bed, in combination with a supporting structure; a mattress supporting frame comprising a back rest, a thigh section and a leg rest arranged in the order named, with the back rest and thigh section hinged to each other and to said supporting structure and means joining said thigh section to said leg rest, said last means including a pair of hinges spaced from each other longitudinally of the bed a distance materially less than the longitudinal dimension of either said thigh section or leg rest, and means for causing said hinges to selectively assume positions in which their common plane lies either in the general plane of the thigh section or in the general plane of the leg rest, whereby to vary the effective length of the thigh section.

2. In an invalid's bed, in combination with a supporting structure; a mattress supporting frame including a back rest, a thigh section and a leg rest arranged in the order named, with the back rest and thigh section hinged to each other and to the supporting structure and means providing a pair of transversely extending hinges,

spaced from each other longitudinally of the bed, joining said thigh section to said leg rest, means for lifting said thigh section, means for selectively maintaining said hinges with their common plane parallel to said thigh section, said means being releasable to cause said leg rest to drop downwardly by gravity with reference to said thigh section, until said hinges assume a position in which their common plane lies in the general plane of the leg rest, whereby to vary the effective length of the thigh section.

3. In an invalid's bed, in combination with a supporting structure, a mattress supporting frame including a back rest, a thigh section and a leg rest arranged in the order named, with the back rest and thigh section hinged to each other and to the supporting structure, lift mechanism for exerting lift against the thigh section so as to elevate the thigh section and leg rest, and means including a pair of transverse, parallel hinges connecting said thigh section to said leg rest on axes that are spaced from each other, and means for selectively maintaining said hinges in positions in which their common plane is aligned with the general plane of the thigh section, said means being releasable to cause the leg rest to drop downwardly by gravity with reference to the thigh section, until the hinges assume a position in which their common plane is aligned with the general plane of the leg rest.

4. In an invalid's bed, in combination with a supporting structure, a mattress supporting frame comprising a back rest and a thigh section hinged to each other and to said supporting structure on a transverse axis, the adjacent ends of said back rest and thigh section being spaced from each other to provide a gap between said back rest and thigh section, and a leaf of flexible sheet metal spanning said gap, said leaf being hinged to said back rest and thigh section on transverse axes that lie below the hinge axis on which the back rest and thigh section are hinged to the supporting structure when said back rest

and thigh section are in their lowered, horizontal positions, and that lie above said hinge axis when said back rest and thigh section are in their elevated positions.

5. In an invalid's bed, in combination with a supporting structure, a mattress supporting frame comprising a back rest, a thigh section and a leg rest arranged in the order named, with the back rest and thigh section hinged to each other and to the supporting structure on a main hinge axis, and with the thigh section and leg rest hinged to each other on a knee hinge axis that is adapted to be elevated, said thigh section and back rest having adjacent ends that are spaced apart to define a gap, and a leaf of flexible sheet metal spanning said gap and hinged at its opposite edges to said back rest and thigh section, on hinge axes that lie below said main axis when the back rest and thigh section are in their lowered positions and that lie above said main axis when the back rest and thigh section are in their elevated positions, and with said last two mentioned hinge axes closer together in the elevated positions than in the lowered positions, whereby to cause said leaf to bow downwardly in a broad curve when in the elevated position.
